HAIR CLAMP FOR PERMANENT WAVE APPARATUS

Ira S. Mosher, East Orange, N. J.

Application February 25, 1935, Serial No. 7,938

4 Claims. (Cl. 132—33)

This invention relates to an improved form of hair clamp for use in permanent wave apparatus.

In permanent wave apparatus as previously used, it has been customary to clamp each lock 5 of hair adjacent the roots thereof with a clamp, to pass the lock of hair through a guard and place the same over the clamp and thereafter to wind the lock of hair upon a roller and apply heat by means of a heating pad to the lock of 10 hair thus wound, to impart a permanent wave to the lock of hair. Unless the clamp used as a part of this apparatus clamps the strands of hair tightly, there is a tendency for the roller to pull the hair and for the chemical solution produced 15 by the moistened heating pack to leak through the clamp and burn the scalp. Moreover, should the operator wind the lock of hair upon the roller before passing said lock of hair through the guard, it is necessary to unwind the hair from 20 the roller before the guard can be placed in proper position, thus causing considerable delay.

One object of this invention is a more efficient clamp for a permanent wave apparatus.

Another object is a clamp which will prevent 25 the hair from being pulled when wound upon the roller.

Another object is to prevent the chemical solution produced by the heating pack from passing through the clamp to the scalp.

Another object is to save the time lost due to 30 the failure to insert the guard before winding the hair upon the roller.

Other objects will appear from the detailed description which follows.

35 In the drawing comprising but a single sheet of six figures numbered Figs. 1 to 6 inclusive:

Fig. 1 is a plan view of the clamp in open position with certain of the parts shown in section;

Fig. 2 is a plan view of the clamp in closed position with certain of the parts shown in section;

Fig. 3 is a side elevation of the clamp and roller assembly with a lock of hair ready for winding;

Fig. 4 is a side elevation partly in section taken 45 along the line 4—4 of Figure 5 looking in the direction of the arrows;

Fig. 5 is an end view; and

Fig. 6 is a perspective view of the several parts in exploded form.

50 Like reference characters designate corresponding parts throughout the several figures of the drawing.

Clamp 10 includes tie rod 11 having an elbow-shaped end piece 12 secured to one end of said 55 tie rod in any suitable manner, as by means of

a rivet 13. End piece 12 includes a wedge-shaped extension portion 14. This wedge-shaped extension may be triangular, conical, or otherwise formed, so as to center in the frustoconical opening 26 formed in the tubular metal clamp member 24. End piece 12 is provided with a U-shaped recess 15 for receiving the guideway 37 of roller 35. The opposite end of tie rod 11 may be bent as indicated at 16, and is pivotally connected at 18 to the end piece 17 by means of a nut and bolt, or other suitable device. End piece 17 is bent at right angles to form a shoulder 19 having a shoulder post 19a for engaging in the notched end 36 of roller 35. End piece 17 is likewise provided with a wedge-shaped extension portion 20 which may be triangular, conical, or otherwise formed, so as to constitute a centering device for the frustoconical opening 27 formed in the tubular metal clamp member 24.

A locking lever 22 is pivoted at 21 to the end 20 piece 17 by means of a rivet, or other suitable device, defining a pivot post for the lever. One end of locking lever 22 forms a cam-shaped roller 23 operable to co-operate with the extension member 32 to lock clamp members 24 and 29 25 together. Clamp member 24 is surrounded by a tubular rubber cover 25. Said clamp member is preferably tubular, the bore 28 of clamp member 24 tending to reduce the weight of the device. Bore 28 is bevelled at its opposite ends to define 30 frustoconical openings 26 and 27 for receiving the wedge-shaped extensions 14 and 20 in the manner previously described.

The tubular metal clamp member 24 is provided with a supplemental metal clamp member 35 39. Member 29 is flattened on the side adjacent to member 24 so as to present a substantial gripping area for clamping the hair between the tubular rubber covers 25 and 34, thereby preventing the lock of hair from being drawn through 40 clamping members 24 and 29 when roller clip 35 is rotated to wind the lock of hair upon roller 38. Clamp member 29 is provided at one end with an ear 30, which is pivoted at 31 to the end piece 12 by means of a rivet, or other suitable device, 45 constituting a pivot post for ear 30. Tie-rod 11 and end piece 12 thus in effect form a framework whereon clamp members 24 and 29 are adjustably supported. At its opposite end supplemental metal clamp member 29 is provided with an extension 50 piece 32 for engaging roller cam 23. Extension piece 32 is recessed at 33 to receive and lock roller cam 23 when a lock of hair has been placed in proper position between clamp members 24 and 29 (see Figs. 2 and 6).

A roller clip 35 is used in association with clamp 10. Said roller clip includes a roller 38 journalled in a notched end member 36. The opposite end of roller 38 is provided with a circumferential guideway 37 adapted to engage in the U-shaped recess 15 of clamp 10. Roller clip 35 is also provided with a clamping trigger 39, concavely curved to conform to the contour of the roller 38, said trigger being pivoted at 40 relative to the roller, so that by the movement of clamping trigger 39 the end of the lock of hair may be wound about roller 38 (see Fig. 6) and the clamping trigger 39 then closed against the hair wound on roller 38 to lock the strands of hair in place preparatory to winding the balance of the lock of hair upon the roller 38. Fig. 3 indicates the position of the clamp 10 and roller clip 35 after clamping trigger 39 has been brought into contact with roller 38 and the balance of the lock of hair wound tight upon roller 38 and trigger 39 of roller clip 35.

A chemical pack 41 adapted to be moistened to generate heat is then placed around roller clip 35 (see Figs. 4 and 5) and is retained in place by means of pack holder 42. The pack holder consists of jaw members 43 and 44 (Fig. 6) which are hinged together at their opposite ends by means of jaw hinges 47-47. Jaw members 43 and 44 are also provided with thumb and finger latches 45-45 and a suitable spring 46 co-acting with the thumb and finger latches to tension the jaw members and maintain them in closed position, as shown in Figs. 5 and 6.

The principle of operation is as follows: with the clamp in the open position shown in Fig. 1, a lock of hair is passed between clamp members 24 and 29, clamp 10 being placed on the scalp close to the roots of the hair. Clamp members 24 and 29 are then brought together under finger pressure until roller cam 23 engages in the recess 33 of extension 32, whereupon locking lever 22 is moved from the position shown in Fig. 1 to the position shown in Fig. 2, and the strands of hair are now tightly clamped between the oppositely disposed faces of the tubular rubber covers 25 and 34. The wedge-shaped extensions 14 and 20 coact with the bevelled openings of bore 28 of clamp member 24 to draw clamp members 24 and 29 in substantially parallel position, the wedge-shaped extensions 14 and 20 defining a plurality of adjustable fulcrum points for clamp member 24. This results in bringing all contacting parts of the tubular rubber covers 25 and 34 to substantially equal tension so that all strands of the clamped lock of hair are held under substantially equal tension, thereby preventing any of the strands from being drawn through the clamp when roller clip 35 is operated. The free end of the lock of hair is now placed upon the roller clip as shown in Fig. 6, the clamping trigger 39 is then pressed against roller 38, and roller clip 35 is now rotated to roll the lock of hair upon roller 38 and trigger 39, and roller clip 35 is brought into co-operative relation with clamp 10, as shown in Fig. 3. After roller clip 35 has been brought into proper association with clamp 10 as shown in Fig. 3, the roller 38 is rotated in the U-shaped recess 15 by means of a suitable key inserted in an axially disposed key-way 50 in roller 38 shown dotted and by the rotation of the roller, the slackness, if any, is removed from the lock of hair which is thus tightly wound in proper position. The chemical pack 41 is then placed over the hair and moistened, and pack holder 42 placed around pack

41 as indicated in Figs. 4 and 5. Any tendency for roller 38 to unwind is prevented by the frictional engagement of the hair against rubber covers 25 and 34 and the clamping action of pack 41 and pack holder 42. The chemical solution generated by moistened pack 41 will impregnate the hair rolled on roller clip 35, but owing to the tension exerted upon clamp members 24 and 29 by locking lever 22 no part of this solution will leak through the rubber covers 25 and 34 to the scalp, thus eliminating any risk of burning the scalp with the chemical solution generated by pack 41. After suitable time has elapsed, the operator removes the holder 42, the pack 41, unwinds the hair from roller clip 35, and releases clamp 10.

Clamp member 24 is rotatable about the fulcrum points formed by the wedge-shaped extensions 14 and 20 seated in the frusto-conical openings 26 and 27, thereby permitting the member 24 carrying tubular rubber cover or rubber roller 25 to be rotated, to permit the rubber to wear evenly. Tubular rubber cover or rubber roller 34 may be rotated on the clamp member 29 so as to present an unworn contacting surface opposite the contacting surface of rubber roller 25. The tubular rubber covers 25 and 34 may be renewed when worn, the former by first removing the nut and bolt of pivot 18, and the latter by merely withdrawing the worn out cover 34.

It should be understood that when clamp 10 is closed as shown in Fig. 2, the contacting faces of the rubber rollers 25 and 34 are compressed against the tension exerted by the roller cam 23 in the recess 33 of extension 32, and the pressure between the contacting faces of the rubber rollers 25 and 34 prevents the strands of hair from being drawn through the said rollers when roller 38 is rotated to wind the lock of hair thereon.

What is claimed is:

1. A permanent wave apparatus comprising a clamp, said clamp having a tubular clamp member, the bore ends of said tube being bevelled to define frusto-conical seats, wedge-shaped members seated in said seats, a tie rod interconnecting said wedge-shaped members and pivotally connected to one of them, a supplementary clamp member pivotally connected to the other wedge-shaped member, said supplementary clamp member being moved about said pivot towards and away from said tubular clamp member and having a concave recess in the free end thereof defining a cam seat, and a pivotally-mounted lever-operated cam for engaging with and locking in said cam seat to secure and retain said clamping members in parallel alignment.

2. In a clamp for a permanent wave apparatus and in combination, a first clamping member having the ends thereof countersunk to define wedge-shaped seats, end pieces, said end pieces having wedge-shaped extensions for frictionally engaging the walls of said seats, a tie rod interconnecting said end pieces and pivotally connected to one of them, a second clamping member pivotally connected to the other end piece, said second clamping member being movable about its pivot towards and away from said first clamping member and having a recess in the free end thereof defining a cam seat, and a lever controlled cam pivotally mounted relative to the first clamping member and operable by said lever to engage with and lock in said cam seat to secure and retain said clamping members in parallel alignment.

3. A hair clamp comprising, a framework, a

first clamping member supported on said framework and having a flared end, an end piece pivoted to said framework and bevelled to frictionally engage the walls of said flared end to form a bearing for said clamping member, a complementary clamping member pivoted to said framework and movable towards and away from said first clamping member, and means including a lever operated cam cooperating with said end piece and with the free end of said complementary clamping member for locking said clamping members in parallel alignment.

4. A hair clamp comprising a framework, a first clamping member supported on said frame-

work and having a flared end, an end piece pivoted to said framework and bevelled to frictionally engage the walls of said flared end to form a bearing for said clamping member, a complementary clamping member pivoted to said framework and movable into and out of clamping position relative to said first clamping member, and means cooperating with said end piece and with the free end of said complementary clamping member for bringing said clamping members into, and locking them against movement out of, clamping position.
